UNITED STATES PATENT OFFICE.

A. V. HEYDEN, OF MILWAUKEE, WISCONSIN.

IMPROVEMENT IN SHIFTING CARRIAGE-TOPS.

Specification forming part of Letters Patent No. 59,014, dated October 23, 1866.

To all whom it may concern:

Be it known that I, A. V. HEYDEN, of the city and county of Milwaukee, and State of Wisconsin, have invented a new and useful Improvement in Shifting Carriage-Tops; and I do hereby declare that the following is a full and exact description thereof, reference being had to the accompanying drawings, making a part of this specification, in which—

Figure 1 is a view of the bottom of a carriage-seat with part of my improvement; Fig. 2, a top view of the same with my improvement attached; Fig. 3, a front view of the seat and top-frame; Fig. 4, a cross-sectional view of the seat and top; Fig. 5, a front view of the top-frame detached from the seat; Fig. 6, a cross-sectional view of the top; Fig. 7, front view of seat; Fig. 8, cross-section of seat.

Similar letters of reference in each of the figures indicate corresponding parts.

The nature of my invention consists in a novel arrangement of a carriage top and seat, so that the top can be easily detached and replaced again.

To enable others skilled in the art to make and use my invention, I will proceed to describe its construction and operation.

A is the carriage-seat; B, back of the top-frame; C, metal plate or base of the carriage-top; D and E E, catches or buttons on the seat to confine plate C to the seat; F F, lever-catches on the bottom of the seat to lock the front of the top to the seat; G, cross-lever with which to operate lever-catches F F; H, spring-catch to hold lever G in place when the lever-catches F F are locked; I I, front supports to the top, projecting down through the seat, with slots in said projections for lever-catches F F to lock into.

Operation: When the top is secured to the

seat, to remove it turn the catches D and E E back from over plate C and draw back lever-catches F F, with cross-lever G, spring H being pressed against the seat to let lever G pass over it. Then lift the top from the seat. To replace it, place it back again with supports I I passing through the bottom of the seat. It may then be fastened to the seat by turning catches D and E E over plate C and locking lever-catches F F into the slots in the ends of supports I I. When lever-catches F F are locked in said slots, catches E E are not required to be turned over plate C, and when catches E E are turned over plate C the locking of lever-catches F F may be dispensed with; but in either case, or when both catches E E and lever-catches F F are used, the catch D is indispensable to hold the back part of the top to the seat.

What I claim as my invention, and wish to secure by Letters Patent, is—

1. Attaching all the supports of carriage-top B to a single metal plate, C, and fastening the same to carriage-seat A by means of catches D and E E, substantially as and for the purpose described.

2. A carriage-top with all its supports attached to metal plate C, with standards I I passing through seat A, with slots or notches in their lower ends, into which catches F F are locked by means of lever G, and held in position by spring-catch H, together with catch D, to hold the middle of plate C firmly to seat A, all in combination, substantially as and for the purpose described.

A. V. HEYDEN.
